(57) **CLAIM**

The ornamental design for a pen-shaped injector, as shown and described.

DESCRIPTION

The patent or application file contains at least one drawing executed in color. Copies of this patent or patent publication with color drawings(s) will be provided by the Office upon request and payment of the necessary fee.

FIG. 1 is a perspective view of the pen-shaped injector.

FIG. 2 is front view thereof.

FIG. 3 is a back view thereof.

FIG. 4 is left side view thereof.

FIG. 5 is right side view thereof.

FIG. 6 is top view thereof.

FIG. 7 is bottom view thereof.

FIG. 8 is a perspective view of the pen-shaped injector of FIG. 1 without a cap.

FIG. 9 is front view thereof.

FIG. 10 is a back view thereof.

FIG. 11 is left side view thereof.

FIG. 12 is right side view thereof.

FIG. 13 is top view thereof; and,

FIG. 14 is bottom view thereof.
